United States Patent Office

Des. 190,673

Patented June 20, 1961

190,673

FLASHLIGHT SWITCH

Herman G. Graubner, New York, N.Y., assignor to
Union Carbide Corporation, a corporation of New
York

Filed Nov. 16, 1959, Ser. No. 58,366

Term of patent 14 years

(Cl. D48—24)

Fig. 1

Fig. 2

FIG. 1 is a reduced perspective view of a flashlight switch showing my new design.

FIG. 2 is an elevation of the switch shown in FIGURE 1.

I claim:

The ornamental design for a flashlight switch, as shown.
